CLAIM

The ornamental designs for a digital camera display screen having a graphical user interface, as shown and described.

DESCRIPTION

FIG. 1 is a rear, top, and left side perspective view of a first embodiment of a digital camera display screen having a graphical user interface, showing the new design;

FIG. 2 is a front view thereof;

FIG. 3 is a rear view thereof;

FIG. 4 is a top view thereof;

FIG. 5 is a left side view thereof;

FIG. 6 is an enlarged view of the first image of the graphical user interface shown on the digital camera display screen;

FIG. 7 is an enlarged view of the second image of the graphical user interface shown on the digital camera display screen;

FIG. 8 is a rear, top, and left side perspective view of a second embodiment of a digital camera display screen having a graphical user interface, showing the new design;

FIG. 9 is a front view thereof;

FIG. 10 is a rear view thereof;

FIG. 11 is a top view thereof;

FIG. 12 is a left side view thereof;

FIG. 13 is an enlarged view of the first image of the graphical user interface shown on the digital camera display screen; and,

FIG. 14 is an enlarged view of the second image of the graphical user interface shown on the digital camera display screen.

The appearance of the transitional image sequentially transitions between the images shown in FIG. 6-7 and FIG. 13-14. The process or period in which one image transitions to another image forms no part of the claimed design. This process or period forms no part of the claimed design.

(Continued)

The broken lines in the drawings illustrate portions of the digital camera and the digital camera display screen having the graphical user interface that form no part of the claimed design.
